UNITED STATES PATENT OFFICE

2,428,179

VALVE-SEAT PULLER

Charles Francis Robinson, Carlsbad, Calif.

Application May 12, 1944, Serial No. 535,279

3 Claims. (Cl. 29—275)

1

This invention relates to a device for pulling valve seats from their counterbores in cylinder heads, cylinder blocks, or the like, of internal combustion engines. The valve seats referred to are of ring form and from time to time must be removed and replaced. These valve-seats are tight in the counterbores that operate as seats for them, and require the exertion of some force to dislodge them.

One object of this invention is to provide a device of simple construction for accomplishing the pulling, that is, the removal of such valve-seats.

A device is now in use for pulling valve-seats that includes an extensible bar that is inserted through the opening in the seat, placed in a diametrical position and then extended so that its ends bear against the seat at two diametrically opposite points.

One of the objects of this invention is to produce a tool for this purpose constructed so that the force exerted in pulling the valve seat will be applied substantially all around the periphery of the valve-seat.

In the preferred embodiment of the tool it includes a collet which in its normal or collapsed condition, is adapted to pass through the opening in the valve-seat, and a means is provided for expanding this collet thereafter to enable it to seat against the inner side of the valve-seat.

One of the objects is to provide a rotary member for effecting this expansion and to provide the tool with means for preventing its rotation about its own axis when the collet is being expanded.

Further objects of the invention will appear hereinafter.

The invention consists in the novel parts and combination of parts to be described hereinafter, all of which contribute to produce an efficient valve seat puller.

A preferred embodiment of the invention is described in the following specification, while the broad scope of the invention is pointed out in the appended claims.

In the drawing,

Fig. 1 is a fragmentary section through a cylinder head and showing an ideal section through this device on the section line 1—1 indicated in Fig. 2.

Fig. 2 is a rear end view of the tool removed from the cylinder head.

Fig. 3 is a cross section taken about on the line 3—3 of Fig. 1 and particularly illustrating the mode of operation of the means for preventing rotation of the tool on its own axis when its

handle is being rotated to expand it after it has been thrust through the opening in the valve-seat.

In this specification and drawing this invention is described and illustrated as applied to a tool to be used for pulling the valve seats from the cylinder head of a Diesel type engine.

In practicing the invention, I provide means, preferably consisting of a collet 1, having a head 2 of circumferential form and this head is of a diameter that will enable it to pass through the opening 3 in the valve-seat 4 that is to be pulled out of the counterbore 5 in which it rests. This counterbore, in the present instance, is formed on the inner face of a cylinder head 6, and is typical of the valve-seats, many of which are usually employed in internal combustion engines.

In order to enable the collet head to collapse slightly to pass through the valve-seat, I prefer to provide it with a plurality of substantially radial slots 7, and these slots extend up into the tubular neck 8 of the collet to a point at or near its hub 9 that is fixed on the spindle 10 of the tool. The tubular neck 8 has a counterbore 11 that is of slightly larger diameter than the spindle so as to enable the segments of the neck between the slots to spring inwardly. The head 2 of the collet is formed with an external bead under which a shoulder 12 is located. The inner face of these valve-seats is usually formed with a beveled face 13, and the shoulder 12 in that case would be similarly beveled, that is, on the same angle.

The tool is provided with a handle 14 for expanding the collet to seat its shoulder back of the valve-seat and so as to establish a good working contact between the shoulder 12 and the valve-seat. For this purpose I prefer to provide expander means in the form of a tapered collar 15 that seats in a tapered or conical socket 16 in the outer end of the head.

The tool is constructed so that the rotation of the handle 14 will effect the expanding of the head 2, and this is preferably accomplished by providing a threaded shank 17 on the spindle 10, and by forming the handle 14 with a threaded socket to screw onto the end of the threaded shank. When the handle is rotated by means of the cross bar 18 its inner end forces the expander collar 15 inward and spreads the segments 2a, 2b, and 2c of the head.

A washer 19 may be provided between the end of the handle and the butt end of the collar 15 if desired.

The inner end of the spindle 10 operates as a pilot stem to facilitate insertion of the tool in a

properly centered position. That is to say, the inner end of the spindle would be inserted in the bore of the valve-stem guide or bushing 20. When the tool is inserted in this way, there should be enough clearance to insure that when the inner end of the hub 9 of the collet is stopped by the inner end of the bushing 20, the shoulder 12 will have moved past the valve seat 4. After the tool is in the position illustrated in Fig. 1, then the handle 14 is turned sufficiently to expand the collet slightly and insure that it will not pull through the opening in the valve-seat when the tool is pulled back by a force exerted on the cross bar 18. If the tool sticks, the inner end of the spindle may be struck with a club or mallet or a piece of soft wood, to dislodge the valve seat without danger of burring up the end of the spindle. If desired, a detachable cap may be provided to be put over the inner end of the spindle to receive the blow and at the same time protect the end of the spindle against being burred over.

The device is preferably provided with means for preventing it from rotating on its longitudinal axis when the handle 14 is rotated to expand the collet 2. For this purpose, I prefer to provide the hub 9 of the collet with a lateral finger or long pin 21. This finger should be short enough to insure that it will pass freely through the opening in the valve stem. This finger may be used to secure the collet to the spindle, in which case its inner end would be seated in a hole 22 drilled in through the hub and the side of the spindle (see Fig. 3). This pin should be a press fit in this drilled hole.

When this tool is employed for pulling the valve-seats of a Diesel engine head 6, the long pin 21 will engage against the tubular housing 23 for the Diesel injector valve 24. As soon as this pin engages the side of this housing, the rotation of the tool on its longitudinal axis will be prevented and the handle or nut 14 on the thread of the shank 17 will tighten up the collar 15 in the conical socket 16.

I claim as my invention:

1. In a valve-seat puller for removing a valve-seat or the like from a part carrying the same, the combination of: a spindle; expansible means carried on the spindle having an annular shoulder for engaging the seat; said means at said shoulder being of sufficiently small diameter to pass through the opening in the seat; means carried by the expansible means for engaging said part to prevent the expansible means from rotating; and a rotatable handle carried on the outer

end of the spindle; and means actuated by said handle for expanding said expansible means.

2. In a valve-seat puller, the combination of: a spindle; a collet fixed thereon, said collet having substantially radial slots enabling the same to contract and expand, and having shoulders between said slots for engaging the valve-seat; a threaded shank on said spindle; means mounted on said threaded shank for controlling the said slotted collet to facilitate inserting it and applying it to the valve seat preparatory to pulling the same; and a pin mounted in the collet and projecting laterally therefrom for preventing rotation of the valve-seat puller on its longitudinal axis when the means mounted on the threaded shank is being operated to expand the collet.

3. In a valve-seat puller for removing a valve-seat or the like from a part carrying the same, and having a valve stem guide beyond the seat, the combination of: a spindle; expansible means insertable through the opening in the valve-seat, including a sleeve carried on the spindle, the inner end of said sleeve being located in a position to engage said guide so as to stop the inserting movement of the valve-seat puller when the said spindle has been inserted through the valve-seat opening far enough to bring the expansible means past the valve-seat, said expansible means having an annular shoulder for engaging the seat and adapted to lie opposite the seat when the end of the said sleeve is engaging the valve stem guide; said expansible means at said shoulder being of sufficiently small diameter to pass through the opening in the seat; means carried by the expansible means for engaging said part to prevent the expansible means from rotating; and rotatable means associated with the spindle for expanding the expansible means to engage the valve-seat to secure the same thereto.

CHARLES FRANCIS ROBINSON.
